Joseph Allen

UNITED STATES PATENT OFFICE.

JOSEPH ALLEN, OF PALMYRA, NEW YORK.

COMBINED ANVIL AND VISE.

SPECIFICATION forming part of Letters Patent No. 650,363, dated May 29, 1900.

Application filed March 21, 1900. Serial No. 9,549. (No model.)

To all whom it may concern:

Be it known that I, JOSEPH ALLEN, of Palmyra, in the county of Wayne and State of New York, have invented certain new and useful Improvements in a Combined Anvil and Vise; and I do hereby declare the following to be a full, clear, and exact description of the invention, such as will enable others skilled in the art to which it pertains to make and use it, reference being had to the accompanying drawings, which form part of this specification.

My invention relates to an improvement in a combined anvil and vise combining simplicity in construction and cheapness in manufacturing, as the material which it is made of is hard cast scrap-iron.

After the anvil is cast it requires very little labor to produce a practical tool for the farm, shop, or house and which can be furnished to the trade at a low price; and to this end my invention consists in the combination of the several parts, as will hereinafter be described, and pointed out in the claims.

In the accompanying drawings, Figure 1 is a front view in perspective of my combined anvil and vise. Fig. 2 is a rear view. Fig. 3 is a view of the punch which may be used in connection with my device, and Fig. 4 is a view of a removable horn for the anvil.

A represents the body or web of the anvil, and B the working face, which is hard.

C is the horn to the anvil.

D is the anvil-seat, the bottom of which is smooth.

E is the jaw to the vise, which opens parallel with the jaw on the anvil.

F is the slide or spline, which is cast solid with the jaw, the upper and lower edges of which are -shaped, which goes through the body of the anvil at right angles near the heel end of anvil. The aperture in the body corresponds with the same, keeping the faces of the jaws parallel with one another and preventing any lateral movement of the same. It will be observed that part of the spline enters the anvil-seat D, which further prevents the jaw from wobbling.

G represents two projections under the horn for bending rods.

H is a hardy cast solid to the anvil-seat and body of anvil, handy for opening links or splitting wooden pieces for wedges.

I is the hole near the head for the hardy. 55

J is the punch-block for punching hoops for casks, located under the heel of anvil, a projection from the base.

K is the screw to the vise, which is made of American refined iron within a cast-iron head. 60

L is the lever to the same, with knobs cast on ends of lever.

M M are the slots on the seat to screw anvil to bench.

N is the nut to the screw, which is cast of 65 soft iron, octagon in shape, as long as the anvil is thick. The body of the anvil is cast around it of hard iron. The nut is also serrated, so as to hold it solid in the anvil.

O represents three projections formed triangular around, on the rear side of anvil, and the adjustable horn Q. 70

P is the hardy proper for the anvil.

Q is the adjustable horn. It enters the rear of the body of the anvil and is convenient for 75 forming ferrules and can also be used for a punch and variety of uses.

R is the punch proper, that is furnished with each anvil.

S is an extension of anvil-seat D for the support of the jaw and to hold it in its proper place when the vise is in use, especially when a large body is screwed between the jaws, and is important in a small vise when in use for large pieces to hold and keep the jaws parallel 85 and in upright position. It will be observed that the extension S is a continuation of the base, which further improves the anvil by adding to it a larger base.

T is a hole near the heel for the hardy. 90

U is a hole at the bottom on the side of the hole T for the purpose of letting out any dirt or material which may get in.

V is a square piece of soft wrought-iron cast in the body of the anvil, on each upper side 95 of the aperture, for the passage of the spline through the body of the anvil and extends out front and rear one-fourth of an inch, more or less, which can be bent or upset, which is important, being a cheap way to adjust the 100 spline and jaw in their proper position.

From the foregoing description it will be

seen that my invention is adapted to a wide field of usefulness, being cheaply made and of great practicability at a small cost.

I would have it understood that I do not limit myself to the exact construction shown and described, but hold myself at liberty to make such slight changes and alterations as will come within the spirit and scope of my invention.

Having fully described my invention, what I claim as new, and desire to secure by Letters Patent, is—

1. A combined anvil and vise, comprising a cast anvil provided with an irregular-shaped metal nut united thereto in casting, and a shaped opening extending therethrough beneath the nut, a vise-jaw having the project-

ing slide F, and screw K, engaging, respectively, with the opening and nut, substantially as shown and described.

2. A combined anvil and vise comprising a cast anvil provided with a shaped opening and with an irregular-shaped metal nut and soft wrought-metal pieces V, united with the anvil in casting, a vise-jaw, respectively, engaged with the nut and opening, all connected and arranged as shown and described whereby the soft-metal pieces may be swaged to adjust the vise in relation to the anvil.

JOSEPH ALLEN.
